UNITED STATES PATENT OFFICE.

OTTO P. HOLBROOK, OF SHELBYVILLE, INDIANA.

PAD RACK.

Application filed October 14, 1927. Serial No. 226,223.

This invention relates to a paper file. The chief object of this invention is to provide a file with a series of compartments for progressively exposing papers such as a check filing rack which is adapted to stand upon a flat surface or is adapted to be hung upon a vertical wall or the like.

The chief feature of the invention consists in the formation of a rack or file of the aforesaid character by a plurality of progressively arranged offset loops in multiple and opposed relation, thereby forming a plurality of progressively arranged article receiving compartments or supports.

15 Another feature of the invention consists in the formation of the aforesaid from a minimum amount of wire, the ends thereof being covered by an angular plate which serves as a support or base and as a protective covering for the ends of the wire.

The full nature of the invention will be understood from the accompanying drawings and the following description and claim:

25 In the drawings Fig. 1 is a perspective view of the file or rack with a check or envelope shown dotted therein. Fig. 2 is an enlarged top plan view of the same.

In the drawings 10 indicates a sheet metal base and 11 a sheet metal back, the same formed preferably from a single sheet of metal bent in angular form. The front edge of the base is notched as at 12 forming three tongues, the middle tongue of which is turned inwardly and forms a protected edge. The two end tongues 14 form substantially tubular sockets for a purpose hereinafter set forth. The two side edges of the base 10 are also curled to form substantially tubular sockets 15 for a similar purpose hereinafter set forth. The two sides of the back 11 are likewise curled as at 16 for the same purpose and the top edge 17 of the back is turned inwardly and serves as a reinforcing member or stiffener. The back is provided with a suitable number of apertures 18 which permit the device to be suspended on a vertical wall. The arrangement is such, however, that the device will stand upright when positioned upon a horizontal support such as a table or desk.

Herein a pair of wires are similarly but complementarily formed to form the rack or file arrangement. However, if desired, 55 the two wires forming the rack may be unit-

ed at their forward or rearward ends and thus a single wire produce the same resultant construction. Since two wires are shown in the present drawing a description of one will suffice for them both. The forward end 20 is receivable by a tubular portion 14 and extends towards the center of the base. At the notch 12 there is a standard or vertical portion 21 and lying in the same vertical plane as the end 20 and extending outwardly toward the side, is a top lateral portion 22. Extending downwardly therefrom substantially in the vertical plane of the side is the depending member 23. This extends to the plane of the base or thereabouts and a diagonal base member 24 extends angularly towards the center of the base and the same terminates where it would intersect a plane parallel to the side of the base and including the vertical riser or standard 21. The wire is turned upwardly forming the vertical portion 121 substantially parallel to the vertical standard 21 but projects above the same the desired amount. The wire is continued as at 122 to form the lateral top which is parallel to the top 22 and lies above the same the distance equal to the difference in length between the members 121 and 21 and lies behind the latter the distance that the standard 121 lies behind the standard 21. The lateral top 122 terminates in the plane of the side which includes the vertical depending portion 23 and extending downwardly therefrom is the vertical depending portion 123 which, however, does not extend to the plane of the base, altho it may do so, but terminates short thereof and approximately the distance by which the standards 21 and 121 differ. The end of the depending portion 123 is turned diagonally at 124 toward the center of the base in a plane parallel thereto and lies substantially parallel to the diagonal angular base member 24 and in spaced relation therewith.

The foregoing construction is duplicated as many times as desired, each succeeding substantially open loop formed by the several members 21, 22, 23 and 24 being successively offset from front to rear and being successively offset from the base in progressive elevation. Each of the open loops is substantially similar to the previous loop and the parts thereof may be similarly numbered.

as (N-1) .100 plus 21, (N-1) .100 plus 22, (N-1) .100 plus 23, (N-1) .100 plus 24, where "N" represents the position of the open loop. Thus, the first open loop includes the parts 21, 22, 23 and 24, the second loop parts 121, 122, 123 and 124, and the eighth open loop, if employed, 621, 622, 623 and 624. Herein, however, but six open loops are illustrated and the vertical riser 621 is provided with a lateral top 622 and a vertical depending portion 623 which constitutes the rear standard of the tier of open loops and said vertical standard 623 is receivable by the substantially tubular portion 16 of the back and not only reinforces the back but also is secured in rigid relation thereto. The vertical standard 623 terminates in an angular portion 624 which is receivable by the tubular curled socket 15 of the base side.

A pair of the aforesaid wires similarly but complementarily arranged, are provided and since the two ends of the wires are similarly anchored to the base and back, they are maintained in spaced relation thereby forming two series of compartments, steps or open loops with the several portions lying parallel to each other or lying in the same plane, as the case may be, that is, the two vertical standards 21 and the two depending portions 23 lie in the same plane and are parallel to each other. The two diagonal base portions 24 lie in the same plane but extend towards each other and toward the center of the base. The same applies for each succeeding pair of diagonal base portions, and these base portions serve as a bottom support for letters, checks, or the like indicated by the numeral 50 and shown dotted in Fig. 1.

The two wires may, if desired, be united by a clip or tie member 51 having the eye portions 52 and an intermediate loop or eye 53 by which the entire rack may be anchored upon a single nail or hook upon a wall. If desired, the wires 622 and 621 instead of being arranged as shown, may be turned inwardly towards each other and interlocked with a loop formation and thence proceed toward either side and thence downwardly as at 623—in other words, dispensing with the separate clip. As hereinbefore suggested, the ends 20 of the wire instead of being turned outwardly may be turned inwardly and lie within the curled portion 13 and be united, and thus the entire rack be formed from a single wire having two substantially similar complementary portions.

The invention claimed is:

A device of the character described, comprising a pair of wires each similarly but complementarily formed and each having a plurality of relatively parallel substantially vertical progressively offset standard portions, a similar number of laterally directed top portions extending outwardly from the upper ends of the vertical standards, a similar number of parallel and substantially vertical portions depending from the opposite ends of the top portions, and a similar number of diagonal inwardly and rearwardly directed base portions connected to the lower ends of successive vertical portions for forming successively positioned open loops therewith, and progressively connected thereby.

In witness whereof, I have hereunto affixed my signature.

OTTO P. HOLBROOK.
